UNITED STATES PATENT OFFICE

ALFRED S. DONALDSON, OF NEWARK, NEW JERSEY, ASSIGNOR TO DU PONT VISCOLOID COMPANY, OF WILMINGTON, DELAWARE, A CORPORATION OF DELAWARE

DESIGN FOR A HAND MIRROR OR SIMILAR TOILET ARTICLE

Application filed May 17, 1932. Serial No. 43,826. Term of patent 3½ years.

To all whom it may concern:

Be it known that I, ALFRED S. DONALDSON, a citizen of the United States, residing at Newark, in the county of Essex and State of New Jersey, have invented a new, original, and ornamental Design for a Hand Mirror or Similar Toilet Article, of which the following is a specification, reference being had to the accompanying drawing, forming part thereof.

Fig. 1 is a face view; and

Fig. 2 is an edge view of a hand mirror or similar toilet article showing my new design.

I claim:

The ornamental design for a hand mirror or similar toilet article as shown.

ALFRED S. DONALDSON.
